[57] CLAIM

The ornamental design of a combined table top and support therefor, as shown and described.

DESCRIPTION

FIG. 1 is a perspective view of one embodiment of a combined table top and support therefor embodying my new design;

FIG. 2 is a top plan view thereof;

FIG. 3 is a bottom plan view thereof;

FIG. 4 is a side elevational view, thereof;

FIG. 5 is a front elevational view thereof;

FIG. 6 is a perspective view of a second embodiment of a combined table top and support therefor embodying my design;

FIG. 7 is a top plan view thereof;

FIG. 8 is a bottom plan view thereof;

FIG. 9 is a side elevational view thereof;

FIG. 10 is a front elevational view thereof;

FIG. 11 is a perspective view of a third embodiment of a combined table top and support therefor embodying my design;

FIG. 12 is a top plan view thereof;

FIG. 13 is a bottom plan view thereof;

FIG. 14 is a side elevational view thereof; and

FIG. 15 is a front elevational view thereof.

The broken lines in the drawings are for illustrative purposes only.

FIG. 1**FIG. 2****FIG. 3****FIG. 4****FIG. 5**

FIG. 6**FIG. 7****FIG. 8****FIG. 9****FIG. 10**

FIG. 11**FIG. 12****FIG. 13****FIG. 14****FIG. 15**
